US0D1084574S

(12) **United States Design Patent** (10) **Patent No.:** **US D1,084,574 S**
(45) **Date of Patent:** **** Jul. 15, 2025**

(54) **FLOOR BRUSH**

(71) Applicants: **Suzhou Rongxuan Electric Co., Ltd,**
Suzhou (CN); **Yida Electric**
Technology (Suzhou) Co., LTD,
Suzhou (CN)

(72) Inventors: **Tianbo Xing**, Suzhou (CN); **Jundong**
Xing, Suzhou (CN)

(73) Assignees: **Suzhou Rongxuan Electric Co., Ltd,**
Suzhou (CN); **Yida Electric**
Technology (Suzhou) Co., LTD,
Suzhou (CN)

(**) Term: **15 Years**

(21) Appl. No.: **29/980,811**

(22) Filed: **Dec. 27, 2024**

(30) **Foreign Application Priority Data**

Dec. 20, 2024 (CN) 202430811785.5

(51) **LOC (15) Cl.** **15-05**

(52) **U.S. Cl.**
USPC **D32/31**

(58) **Field of Classification Search**
USPC D32/17, 18, 21, 22, 23, 24, 25, 31, 32;
D15/199
CPC .. A47L 11/24; A47L 11/4005; A47L 11/4066;
A47L 9/009; A45L 2201/00

(57) **CLAIM**

The ornamental design for a floor brush, as shown and described.

DESCRIPTION

FIG. 1 is a first perspective view of a floor brush showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the floor brush that form no part of the claimed design.

1 Claim, 8 Drawing Sheets
